HAIR-WAVING SPACER

James E. Snyder, Pittsburgh, Pa., assignor, by
mesne assignments, to Rol-O-Wave, Inc., New
York, N. Y., a corporation of New York

Application March 30, 1940, Serial No. 327,008

7 Claims. (Cl. 132—36.1)

This invention relates to a device for waving hair and, in particular, to a spacer or clasp for holding separate locks of hair during the application of a permanent wave.

It is customary in giving permanent waves, to use a spacer next the scalp for holding a lock of hair while being treated to effect a permanent wave therein. Various types of spacers have been used heretofore but none of them, so far as I am aware, has performed its intended function in the most desirable manner. The spacers used heretofore, furthermore, have been characterized by excessive bulk and weight and are, therefore, objectionable from the standpoint of the customer.

I have invented a novel spacer which is particularly adapted for the permanent waving of hair by the aid of the device disclosed in co-pending application Ser. No. 329,445, filed April 13, 1940, by Jemima A. McLain.

In a preferred embodiment, the spacer or clasp of my invention comprises a pair of wings pivotally connected, each wing having substantially the shape of a right triangle, the wings being so related that when closed, their altitudes are adjacent. One of the wings has a locking lever pivoted thereto adapted to hold the wings in closed position about a lock of hair. Further details and advantages of the invention will become apparent during the following complete description thereof which is to be read in connection with the accompanying drawing illustrating a preferred embodiment. It will be understood, however, that the invention may be embodied otherwise than as shown, within the scope of my broad claims. In the drawing—

Fig. 1 is a plan view of my spacer, with parts omitted;

Fig. 2 is a side elevation;

Fig. 3 is a plan view to enlarged scale showing the spacer in open position;

Fig. 4 is a perspective view of a detail;

Fig. 5 is a perspective view showing the clasp in place, ready for reception of the permanent waving device;

Fig. 6 is a sectional view taken along a central plane parallel to the face of the spacer, parts being shown in elevation;

Fig. 7 is a sectional view taken along the line VII—VII of Fig. 6; and

Fig. 8 is a perspective view of one of the wings before assembly.

Referring now in detail to the drawing, the spacer of my invention is indicated generally at 10 and comprises a pair of wings 11 and 12

pivotal connected. As shown in the drawing, the wings are so disposed that when the spacer is closed, the longer sides of the wings are disposed adjacent each other. The wings 11 and 12 may preferably be made by bending a flat sheet of material having substantially the shape of an equilateral triangle, into the form best shown in Fig. 8 and providing spaced top and bottom surfaces 13 and 14 and a connecting side wall 15.

A bearing tongue 16 is secured to and extends outwardly from the apex of the wing 12. The tongue is secured to the wing by a rivet 17. The wing 11 is pivoted to the tongue 16 by a rivet 18. The inner sides of the wings are notched as at 19 and are provided with resilient gripper pads 20 of rubber or similar material.

A locking lever 21 is pivoted to the wing 11 and has a tongue 22 adapted to engage the connecting side wall of the wing 12, as shown in Fig. 6. The extreme end of the locking lever projects beyond the wing 12 when the spacer is closed, to facilitate pulling out the lever and opening the spacer.

The spacer is provided at each corner with feet 23 adapted to engage the scalp and maintain the body of the spacer at a distance therefrom.

In using the spacer of my invention, the hair is gathered in a lock as indicated at 24. With the wings 11 and 12 open as shown in Fig. 3, the spacer is disposed about the lock of hair and the wings thereof closed with the lock in alignment with the notches 19. The rubber pads 20 yield adjacent the notches as the spacer is closed about the lock with the result that the hair is gripped tightly with a uniform pressure at all points and is maintained in a substantially cylindrical lock without any tendency to spread along the line of division between the wings 11 and 12. When the spacer has been closed, the locking lever 21 is actuated to the position shown in Fig. 6 whereby the wings are tightly held together.

When properly applied, the spacer bears but lightly on the scalp and because of its low weight is not apt to cause discomfort. When the permanent waving operation is completed, the locking lever 21 is opened and the spacer removed from the strand.

It will be apparent from the foregoing description that the invention is characterized by numerous novel features and advantages, some of which have already been mentioned. The device is simple in construction and can be manufactured at relatively low cost. The shape of the

spacer permits a shape, the desired number of them to be disposed in close proximity without interfering with each other, in the region of the head which is to be subjected to permanent wav- ing. When the spacer is closed about a lock of hair, and the locking lever actuated, there is no danger of accidental opening of the spacer. On the contrary, the spacer tightly grips the lock of hair until the locking lever is positively actuated to permit the wings to be spread apart.

Although I have illustrated and described but a preferred embodiment of the invention, it will be understood that changes in the construction or arrangement thereof may be made without departing from the spirit of the invention or the scope of the appended claims.

I claim:

1. A spacer comprising a pair of members each having substantially the shape of a right triangle, said members lying in the same plane and being pivotally connected with their corresponding altitudes adjacent each other.

2. A spacer having generally the shape of an equilateral triangle and composed of a pair of members shaped like a right triangle and pivotally connected with their corresponding altitudes adjacent.

3. A spacer comprising a pair of members each having substantially the shape of a right triangle, said members lying in the same plane and being pivotally connected with their corresponding altitudes adjacent each other, each of said members comprising sheet metal in the form of

an equilateral triangle bent double along its altitude.

4. A spacer having generally the shape of an equilateral triangle and composed of a pair of members shaped like a right triangle and pivotally connected with their corresponding altitudes adjacent, said spacer having spaced feet projecting therefrom adapted to engage the head of the wearer.

5. A spacer comprising a pair of members each having substantially the shape of a right triangle, said members lying in the same plane and being pivotally connected with their corresponding altitudes adjacent each other, and a locking lever pivoted on one member and engageable with the other.

6. A spacer comprising a pair of members each having substantially the shape of a right triangle, said members lying in the same plane and being pivotally connected with their corresponding altitudes adjacent each other, said altitudes being notched to receive a lock of hair therebetween.

7. A spacer comprising a pair of members each having substantially the shape of a right triangle, said members lying in the same plane and being pivotally connected with their corresponding altitudes adjacent each other, said altitudes being notched to receive a lock of hair therebetween and having a surface layer of compressible material thereon.

JAMES E. SNYDER.
